UNITED STATES PATENT OFFICE.

MAHLON S. CONLY, OF LOS ANGELES, CALIFORNIA.

OIL-BURNER.

No. 876,898.

Specification of Letters Patent.

Patented Jan. 14, 1908.

Application filed April 4, 1907. Serial No. 366,451.

To all whom it may concern:

Be it known that I, MAHLON S. CONLY, a citizen of the United States of America, residing at Los Angeles, county of Los Angeles, 5 State of California, United States of America, have invented a certain new and useful Oil-Burner; and I do hereby declare the following to be a full, clear, and exact description of the invention, such as will enable others 10 skilled in the art to which it appertains to make and use the same.

This invention relates to oil burners and more particularly to that class of burners in which the oil is sprayed or atomized by a jet 15 of steam or air.

One of the objects of this invention is to provide a burner, in the construction of which few mechanical processes will be necessary and those of the simplest and cheapest 20 kind.

It is also an object to make the parts subject to the eroding action of the issuing jet, easily and cheaply renewable.

A further object is to make these parts so 25 that a fresh portion thereof may be moved to the position of wear as required.

Referring to the accompanying drawing Figure 1 is a top plan view; Fig. 2 is a vertical section; Fig. 3 is a plan of one of the 30 newable parts.

Reference numeral 1 designates a cup-shaped casing having a hollow post 2 in the central part thereof, the lower end of which is threaded to receive a cap screw 3, beneath 35 the head of which is washer 4, pressing on the cover 5. Cover 5 has a flange 6, having a portion thereof cut away. A flat ring 7, the inner edge of which is preferably beveled, rests upon the top edge of cover 5, upon it 40 rests a disk 8, a portion of the periphery of which is cut away, to match cover 5, as shown in Fig. 3. The central portion of disk 8 rests on a shoulder on post 2, said shoulder being slightly lower than the top of ring 7 45 when the latter is in place. Upon disk 8 a ring 9, similar to ring 7, rests. A steam port 10 is formed in post 2, and a steam supply pipe 11 communicates with the opening in said post. An oil supply pipe 12 leads to 50 casing 1. The rear ends of these pipes are connected to fitting 13, wherein is a three-way valve 14. The lower end of fitting 13 receives the end of oil pipe 15, having a valve

16, and the upper end receives steam pipe 17 having valve 18.

The mode of operation of this invention is as follows: Three-way valve 14 being turned so as to close the passage from pipe 17 to pipe 15, and open that from pipe 17 to pipe 11, valves 17 and 18 are opened. The steam 60 flows through pipe 11 and the hollow post 2 to the interior of the cover 5, and issues between rings 7 and 9 and the place where disk 8 and cover 5 are cut away. The oil flows through pipe 12 to the casing 1 and meets 65 the steam as it issues between the plates 7 and 9 and is atomized thereby.

It will be readily understood that the oil is heated and rendered more fluid by contact with the casing 1 and plate 2, which are 70 heated by the steam on its way to the orifice.

When it is desired to clean the apparatus, valve 16 is closed and valve 14 turned to allow steam to flow through pipe 12, whereby all deposits are driven out. As rings 7 and 75 9 become worn they may be turned to bring a new portion opposite the cut-away portions of disk 8 and cover 5. It is only necessary to slacken cap screw 3 in order to allow this to be done.

I claim:

1. In a liquid fuel burner, a casing, a diaphragm dividing said casing, said diaphragm having a portion cut from its edge, a rotatable wear-resisting member at each side of 85 said diaphragm and means to supply liquid fuel and steam respectively to the spaces on each side of said diaphragm.

2. In a liquid fuel burner, substantially cup shaped upper and lower casing members, 90 a flexible disk held between said members, a conduit leading to each of the spaces within said upper and lower members and rotatable wear-resisting rings on each side of said flexible disk.

3. In a liquid fuel burner, a casing member, a post therein, a shoulder on said post, a disk on said post contacting with said shoulder, a ring on each side of said disk, a lower casing member having a portion of its 100 circumference rabbeted and means to clamp said members together.

4. In a liquid fuel burner, a casing member, a post within said member, a shoulder on said post, said shoulder being in a plane 105 passing outside the rim of said member, a

flexible disk on said post, a second casing member and means to clamp said members together so that fluid-tight joints are formed at the edge of said disk and between said shoulder and said disk.

In testimony whereof I have signed my name to this specification in the presence of

two subscribing witnesses at Los Angeles, county of Los Angeles, State of California, this 30th day of April, A. D. 1907.

MAHLON S. CONLY.
